UNITED STATES PATENT OFFICE.

WILLIAM ANDERSON, OF WESTMINSTER, ENGLAND.

MOUNTING FOR HEAVY ORDNANCE.

SPECIFICATION forming part of Letters Patent No. 439,570, dated October 28, 1890.

Application filed July 10, 1889. Serial No. 317,001. (No model.)

To all whom it may concern:

Be it known that I, WILLIAM ANDERSON, engineer, a subject of the Queen of Great Britain, residing at 3 Whitehall Place, in the city 5 of Westminster, England, have invented a Disappearing-Gun Mounting, of which the following is a specification.

This invention has for its object a disappearing-gun mounting which is sufficiently 10 portable to be moved from place to place along a railway.

It consists of a ring-frame on which is a roller-track, and on the underside of the roller-track there are brackets resting upon the axles 15 of wheels, which support the structure and can convey it along a railroad when it is required to move from place to place. Between the wheels, below the roller-track and parallel with the rails, a hydraulic storage-cylinder 20 is carried in a horizontal position. The storage-cylinder contains a piston, and also steel springs. When the gun recoils, liquid is driven, as hereinafter explained, into the Storage-cylinder, driving in the piston against 25 the resistance of the springs. The compressed springs when released return the gun to the original position. The storage-cylinder is not attached to the ring-frame, but to an upper frame which rests upon a ring of rollers running 30 upon the roller-track, and the parts which connect the storage-cylinder below the ring-frame with the frame above it pass through the central opening in the ring-frame. The upper frame at its fore part carries a 35 horizontal axis on which are two lever-arms. The trunnion-bearings are at the upper ends of these arms, and the gun is carried by them. The arms are supported in approximately an upright position by a ram working in a hydraulic cylinder called the "recoil-cylinder." The ram is hollow, and a connecting-rod passes 40 from a cross-bar attached to the arms, at a short distance above the axis to the inner end of the ram, so when the gun recoils the ram is driven in and liquid is displaced from the recoil-cylinder and is received into the storage-cylinder. Behind the trunnions the gun is 45 connected by other arms with toothed racks, which can be raised and lowered by gearing upon the upper frame, and so the requisite elevation is given to the gun. In the passage

between the recoil-cylinder and the storage-cylinder there is a loaded valve, which offers a certain resistance to the passage of the liquid and so controls the recoil, and this 55 valve also prevents the immediate return of the liquid from the storage-cylinder. When it is desired to raise the gun to the firing position, the valve can be lifted from its seat by turning a handle provided for the purpose. 60

Figure 1 is a side elevation, partly in section, of a gun-mounting in accordance with my invention. The gun is in the firing position. Fig. 2 is a plan. The gun is in the position it assumes on recoil. 65

a are the rails upon which the gun-mounting (which is semi-portable) stands.

b are wheels standing on the rails *a* and supporting the under or ring frame *c*.

c is a roller-track upon the ring-frame. 70

d are rollers. Their axes are set radially and held in a light frame consisting of two hoops, one on the outer and the other on the inner side of the rollers.

e is an upper frame resting upon the rollers *d*. 75

f is a storage-cylinder. It is connected with the upper frame *e* by connecting parts *e'* passing down through the center of the ring-frame *c*.

f' is the piston in the storage-cylinder, and 80 *f²* *f²* are the springs.

g are lever-arms. They are mounted upon an axis *g'*, carried by the upper frame *e*.

h is the gun, which the lever-arms *g* carry by its trunnions. 85

i are other arms supporting the gun at its breech end. They are jointed to a ring upon it and descend to toothed racks *k* *k*, to which they are also jointed. The racks are held in guides, in which they are movable longitudinally, and they engage with pinions, which (through intermediate gear, as shown) can be turned by means of the hand-wheel *l*. The axes of the hand-wheel and gearing are carried in bearings upon the frame *e*. 90

m is the recoil-cylinder. It is fixed on the frame *e*, and in it a ram *n* works.

o is a connecting-rod jointed to the lever-arms *g*, and also to the inner end of the hollow ram. 100

p is a pipe connecting the recoil-cylinder with the storage-cylinder.

q is a spring-loaded valve in the pipe *p*, which opens to allow liquid to pass into the storage-cylinder, but closes against return.

r is a screw-spindle with a handle *r'*, which 5 when turned serves to lift the valve from its seat; or in place of lifting this valve a bypass may be opened.

s is a buffer, which receives the breech end of the gun when it descends.

10 *t* is a hand-wheel turning a pinion *t'*, which gears into teeth on the frame carrying the rollers *d*. By turning the wheel *t* the gun is trained in aiming.

u is a shield over the gun, supported by pillars from the frame *e*.

What I claim is—

1. The combination, in a disappearing-gun mounting, of a ring-frame, wheels on which said frame is supported, a roller-track on said frame, an upper frame supported on said track, a horizontal storage-cylinder containing liquid, a piston and springs arranged beneath the ring-frame, the connections *e'*, extending through the ring-frame and securing the storage-cylinder to the upper frame, the gun, lever-arms mounted on the upper frame in which the gun is supported, the recoil-cylinder and piston connected with said arms, and

25 the gun, lever-arms mounted on the upper frame in which the gun is supported, the recoil-cylinder and piston connected with said arms, and

connections or passages between the recoil-cylinder and the storage-cylinder.

2. The combination, in a disappearing-gun mounting, of a ring-frame mounted on wheels and with a roller-track upon it, an upper frame supported on the roller-track, a horizontally-arranged storage-cylinder containing liquid, also a piston and springs arranged below the ring-frame, connections between the storage-cylinder and the upper frame, lever-arms mounted on the upper frame, the gun supported thereby, other arms connecting the gun with the upper frame, elevating-gear for adjusting these arms, a recoil-cylinder fixed to the upper frame, a hollow ram working in the recoil-cylinder, a rod connecting the lever-arms with the inner end of the hollow ram, a pipe connecting the recoil-cylinder with the storage-cylinder, and an automatic non-recoil valve in connection with this pipe preventing the immediate return of liquid from the storage-cylinder after recoil, but not preventing its being passed back in order to again raise the gun.

WILLIAM ANDERSON.
